UNITED STATES PATENT OFFICE.

GEORGE ALBERT LYON, OF PHILADELPHIA, PENNSYLVANIA.

RESILIENT FRONT BUFFER.

Application filed October 25, 1921. Serial No. 510,293.

To all whom it may concern:

Be it known that I, GEORGE ALBERT LYON, a citizen of the United States, and resident of Philadelphia, county of Philadelphia, 5 State of Pennsylvania, have made a certain new and useful Invention Relating to Resilient Front Buffers, of which the following is a specification, taken in connection with the accompanying drawing.

This application is a continuation in part 10 of my co-pending application Serial No. 351,818, filed January 16, 1920, that is, it contains subject matter taken therefrom.

This invention relates especially to 15 silent buffers or buffer front members for automobiles or other vehicles in which spring steel or other resilient strip is used for the buffer front to secure increased resilient yielding action under collision conditions. One or more strips of spring steel or other suitable material may be used to form the buffer front which may comprise end loops formed by bending the strip back upon itself in the same or opposite direction 20 so that such strip ends may be clamped or otherwise connected adjacent the ends of the central impact receiving portion of the buffer front. The strips which form the loops may in some cases be bent forward to 25 ward the buffer front strip adjacent each end of the central impact receiving portion of the buffer front where all of the spring strips may be clamped together and in this case additional spring yielding action is 30 secured when the attaching members of spring steel strip or other construction are clamped or secured to or formed integral with the end loops. Although the entire buffer front 35 may be made of a single piece or strip of such resilient material it may, if desired, be formed of two strips which may in some cases be of generally similar shape and have overlapping portions which may be adjustably or otherwise connected together to 40 form a double thickness re-enforced portion at the central impact receiving part of the buffer front. This type of construction also has practical advantages, since it makes possible a smaller package when 45 the buffer is shipped in disassembled condition. In many cases it is advantageous to have the end loops formed integral with the attaching members and connected thereto through one or more curved resilient portions 50 so as to give increased resilient cushioning action between these parts.

The accompanying drawing shows in a somewhat diagrammatic way a number of illustrative embodiments of the invention in plan view.

Fig. 1 is a plan view showing an illustrative form of buffer and,

Figs. 2 and 3 are similar views showing other illustrative arrangements.

In the form of buffer shown in Fig. 1 the 65 buffer members may be formed of one or more strips of tempered spring steel or other suitable resilient material which may, for example, be a quarter to three-eighths of an inch thick and one and a quarter to two and 70 a quarter inches or more wide and the width of the strips may advantageously be arranged vertically when the buffer is secured or applied to an automobile or other vehicle so as to give the greatly increased vertical 75 rigidity of the parts which is desirable under running conditions. The buffer front strips, such as 4, 9, which may be arranged in reinforcing position, may before hardening and tempering have their ends bent 80 around so as to form end loops 3, 8 which are preferably inclined rearwardly somewhat as indicated and the rear strips or sides of these end loops may advantageously be brought toward or against the other front 85 strips to which they may be closely secured or clamped, if desired. As indicated in Fig. 90 1, these end loop strips may be carried inward and backward in such curved portions as 2, 7, for instance, to give increased resilience and then carried backward to form the attaching members 1, 6, which may be clamped or secured to the automobile frame in any suitable way. The overlapping reinforcing front strips 4, 9 may be clamp or secured together by any suitable clamping devices such, for example, as the clamping devices 11, 12 which may have rearwardly 95 extending members fitting closely around the edges of the buffer strips and clamped there- 100 to by the bolts 13 which may, if desired, also clamp the rear end loop strips to the other front strips of the buffer adjacent the ends 5, 10 of these front strips. In this way ample lateral adjustment is secured so that the buffer can fit automobile frames having different widths and a simple and cheap construction is thus produced which has considerable added strength and stiffness because the end loop portions are initially substantially or completely closed.

In the arrangement shown in Fig. 2 the

end loops 16, 22 have their forward strips 17, 23 inturned so as to extend inward at least to the center of the buffer end, as indicated, the ends 18, 24 of these strips may overlap 5 in some cases, one of the strips being bent backward or offset slightly as at 19 for this purpose. With this construction it is desirable to have one or more front connecting reinforcing strips or members such as 25 10 extending more or less across the buffer front and connected to the other front strips as by the clamping devices 28, 30 which may be located adjacent the ends 26, 27 of this front reinforcing member. These lateral 15 connecting devices may also hold in substantially closed position the rear strips or members of the end loops which may be continued rearward as the curved resilient portions 15, 21 connected to or integral with the attaching members 14, 20. With this type of buffer it is desirable to have one or more central 20 clamping devices such as 29 clamping together in laterally adjusted position the front strips adjacent the central portions 25 thereof.

Fig. 3 shows another illustrative arrangement in which the substantially closed end loop portions 33, 38 of the buffer may have their rear strips integral with the bent 20 portions 32, 37 and attaching members 31, 36, if desired. The front portions or strips of these end loop members may be carried inward sufficiently to connect them to the other front strips, preferably in connection 25 with aligning means or portions to hold the inner ends of these strips in vertical alignment with the others. These inwardly projecting strips 34, 39 connected with the end loops may extend inward part way to the 30 center of the buffer front and may, if desired, have rearwardly extending aligning tips or portions 35, 40 extending through adjusting aligning slots 43, 44 in the rear connecting reinforcing strip or member 41. In order to further strengthen and reinforce the buffer front and give it a more finished appearance a front connecting strip or member 42 may be arranged in overlapping position in front of the other strips and have its ends 45, 46 extend to or through the clamping connecting devices 49, 50 enclosing these buffer front strips and holding them together as well as engaging or enclosing the rear portions of the end loop members as indicated.

This invention has been described in connection with a number of embodiments, forms, proportions, parts, arrangements, materials, methods of connection and use, to the details of which disclosure the invention is not of course to be limited, since what is claimed as new and what is desired to be secured by Letters Patent is set forth in the appended claims:

1. The automobile buffer comprising two

similar spring steel strip members each having an end loop, a curved resilient portion and a connected rearwardly extending attaching member and having a front impact receiving portion extending inward from 70 said loop to overlap and reinforce the corresponding portion of the other member throughout the central part of the buffer front between said attaching members and clamping devices to hold together said overlapping impact receiving portions and the adjacent rear portions of said end loops.

2. The automobile buffer comprising two similar spring steel strip members each having a substantially closed end loop, a curved 80 resilient portion and a connected rearwardly extending attaching member and having a front impact receiving portion extending inward from said loop to overlap and reinforce the corresponding portion of the other 85 member and clamping devices to hold together said overlapping impact receiving portions.

3. The automobile buffer comprising two spring steel strip members each having a 90 substantially closed end loop and a rearwardly extending attaching member and having a front impact receiving portion extending inward from said loop to overlap 95 and reinforce the corresponding portion of the other member and clamping devices to hold together said overlapping impact receiving portions.

4. The automobile buffer comprising two spring steel strip members each having a 100 substantially closed end loop and a rearwardly extending attaching member, one of said members having a front impact receiving portion extending inward from said loop 105 to overlap and reinforce a transversely extending spring strip member of the buffer front and clamping devices to hold together said overlapping portions and the adjacent portions of said end loops.

5. The automobile buffer comprising two spring steel strip members each having a substantially closed end loop and a rearwardly extending attaching member, one of said members having a front impact receiving portion extending inward from said loop to overlap a transversely extending member of the buffer front and clamping devices to hold together said overlapping portions.

6. The spring strip automobile buffer comprising a multiple thickness reinforced front portion, clamping members securing together the co-operating strips adjacent each end of said buffer front portion and outwardly and rearwardly extending end loops having mutually overlapping reinforcing front strips integral with portions of said reinforced buffer front and having rear strips bent forward into substantial contact with said buffer front portion and securely

connected thereto and attaching members and intermediate curved resilient portions integral with the rear strips of said end loops.

7. The spring strip automobile buffer comprising a multiple thickness reinforced front portion, clamping members securing together the co-operating strips of said buffer front portion and outwardly extending 10 end loops having mutually overlapping reinforcing front strips integral with portions of said reinforced buffer front and having rear strips bent forward into substantial contact with said buffer front portion and securely connected thereto and attaching members integral with the rear strips of said end loops.

8. The automobile buffer comprising a substantially straight multiple thickness reinforced spring strip buffer front portion, clamping members securing together the co-operating buffer front strips adjacent each 20 end of said buffer front portion and outwardly extending end loops having front 25 strips integral with portions of said reinforced buffer front and having rear strips bent forward into substantial contact with said buffer front portion and rearwardly extending attaching members adapted to be 30 connected to the automobile frame and intermediate curved resilient portions integral with the rear strips of said end loops.

9. The automobile buffer comprising a substantially straight multiple thickness reinforced spring strip buffer front portion, clamping members securing together the co-operating buffer front strips and outwardly 35

extending end loops having front strips integral with portions of said reinforced buffer front and having rear strips bent into substantial contact with said buffer front portion and rearwardly extending attaching members adapted to be connected to the automobile frame and intermediate resilient portions integral with the rear strips of said end loops.

10. The spring strip automobile buffer comprising a multiple thickness reinforced front portion, clamping members securing together the co-operating strips on each side 40 of the center of said buffer front portion and outwardly extending end loops having front strips integral with portions of said reinforced buffer front and having rear 45 strips bent forward into substantial contact with said buffer front portion and securely connected thereto and attaching members and intermediate curved resilient portions integral with the rear strips of said end loops.

11. The spring strip automobile buffer comprising a multiple thickness reinforced front portion, clamping members securing together the co-operating strips on each side 50 of the center of said buffer front portion and outwardly extending end loops having front strips integral with portions of said reinforced buffer front and having rear 55 strips bent forward into substantial contact with said buffer front portion and securely connected thereto and attaching members and intermediate curved resilient portions integral with the rear strips of said end loops.

GEORGE ALBERT LYON.
